UNITED STATES PATENT OFFICE

2,144,766

SHOE SEWING MACHINE

Bernard T. Leveque, Wenham, Mass., assignor to
 United Shoe Machinery Corporation, Paterson,
 N. J., a corporation of New Jersey

Application March 12, 1935, Serial No. 10,621
 In Great Britain March 15, 1934

6 Claims. (Cl. 112—47)

The present invention relates primarily to shoe sewing machines, and is herein disclosed as embodied in a curved hook needle lockstitch machine adapted to sew the outsole to the welt and upper of a welted shoe.

The object of the invention is to produce an outsole shoe sewing machine arranged to operate in an improved manner so as to permit the machine to be run at a speed high as compared with the speed of machines of this type at present in commercial use, while feeding the shoe so as to produce a satisfactory seam having stitches evenly spaced and formed in a predetermined uniform manner.

With the above object in view, a feature of the invention relates to an improved work feeding mechanism which will feed the shoe with certainty, regardless of the speed at which the machine is operated, and will avoid any tendency of an overthrow with a consequent lengthening or irregularity in the stitches when the machine is operated at high speed or when the parts become loose or worn with use.

This feature of the invention is embodied in a work feeding mechanism in which the advancing and retracting movements of a feed carriage in the line of feed are produced by means of a toggle, the center joint of which is moved from a point at one side of the line of pivotal centers of the toggle to a point substantially in said line in advancing the feed carriage to feed the work. By actuating the feed carriage in this manner, the carriage is always advanced to the same point and any overthrow of the central joint of the toggle, due to the high speed at which the machine is run or to looseness or wear of the parts, has no appreciable effect on the length or evenness of the stitches.

This feature of the invention contemplates varying the action of the toggle in order to vary the length of feed so as to cause the machine to form stitches of different lengths. To accomplish this result, the invention contemplates varying the path of the central joint of the toggle and, in the specific embodiment of the invention hereinafter described, the variation in the path of the central joint is produced by an adjustment of the pivotal support of the member of the toggle remote from the feed carriage about a center substantially in alignment with the central joint of the toggle when the toggle is in straightened condition.

Certain features of the present invention also consist in novel and improved devices, combinations and arrangements of parts hereinafter de-

scribed and claimed, the advantages of which will be obvious to those skilled in the art from the following description.

An outsole shoe sewing machine embodying the several features of the present invention is illustrated in the accompanying drawings in which Figure 1 is a view in right hand side elevation of the complete machine with the operating parts and supporting brackets removed from the head of the machine; Figure 2 is a view in side elevation of the head of the machine illustrating particularly the parts which have been omitted from Figure 1; Figure 3 is a detail sectional view of the rotary loop taker which is in the form of a shuttle, together with the thread case and bobbin for the locking thread supported therein; Figure 4 is a view in front elevation of the head of the machine illustrated in Figure 2; Figure 5 is a view in rear elevation of the head of the machine illustrated in Figures 2 and 4; Figure 6 is a view in front elevation illustrating on a somewhat larger scale many of the parts illustrated in Figure 4; Figure 7 is a detail plan view partly in section of a portion of the head of the machine with the upper portion of the frame and certain of the operating parts removed; Figure 8 is a detail view in front elevation partly in section illustrating the work feeding mechanism and the take-up mechanism for the needle thread; Figure 9 is a view in front elevation of the work feeding mechanism; Figure 10 is a detail view illustrating the connection between the feeding mechanism and locking thread pull-off or measuring mechanism; Figure 11 is a plan view of the mechanism illustrated in Figure 9; Figure 12 is a detail sectional plan view of a locking mechanism for holding the adjusting lever of the work feeding mechanism securely in adjusted position taken on the line 12—12 of Figure 13; Figure 13 is a detail vertical sectional view of the adjusting lever locking mechanism taken on the line 13—13 of Figure 11; Figure 14 is a detail sectional view taken on the line 14—14 of Figure 11; Figure 15 is a detail view in side elevation of the sewing devices adjacent the sewing point; Figure 16 is a detail sectional view of the mechanism illustrated in Figure 15; Figure 17 is a detail sectional view on a larger scale of certain of the parts illustrated in Figure 16; Figure 18 is a detail sectional view of the supporting structure for the needle, awl and needle guide taken on the line 18—18 of Figure 19; Figure 19 is a detail sectional view taken on the line 19—19 of Figure 18, looking in the direction of the arrow at the lower end of the line; Figure 20 is a detail

sectional view taken on the line 20—20 of Figure 18, looking in the direction of the arrow at the upper end of the line; Figure 21 is a detail sectional view taken on the line 21—21 of Figure 18; Figure 22 is a detail view in front elevation of the thread finger, looper, and welt channeling cutter or fudge knife; Figure 23 is a plan view of the mechanism illustrated in Figure 22, together with the actuating lever for the looper; Figure 24 is a detail view of a hand lever and a portion of the connections through which the edge gage and fudge knife and also the feed mechanism, if desired, may be adjusted; Figures 25 to 34 inclusive are a series of detail views illustrating the operation of the thread handling devices in forming a stitch; Figure 35 is a detail sectional view illustrating in side elevation the take-up, pull-off and thread lock for the needle thread, together with their actuating and controlling mechanisms; Figure 36 is a detail view of a portion of the mechanism illustrated in Figure 35, but looking in the opposite direction and with the parts in a different position; Figure 37 is a plan view of the parts illustrated in Figure 36; Figure 38 is a detail sectional view illustrating particularly the presser-foot actuating and controlling mechanism; Figure 39 is a plan view of certain of the parts illustrated in Figure 38, and also of certain parts of the stopping mechanism illustrated in Figures 42 and 43; Figure 40 is a detail sectional view of the presser-foot mechanism illustrated in Figure 39, taken on the line 40—40 of said figure, the parts being shown in the position they assume when the machine is at rest; Figure 41 is a view similar to Figure 40 with the parts in the position they assume while the machine is in operation sewing a seam; Figure 42 is a detail sectional view of the stopping mechanism taken on the line 42—42 of Figure 44, illustrating the parts in the position they assume when the machine is running; Figure 43 is a view similar to Figure 42 illustrating the parts in the position they assume while the machine is stopped; and Figure 44 is a detail sectional view of the stopping mechanism and certain other parts of the machine taken on the line 44—44 of Figure 43.

The work feeding mechanism illustrated in the drawings is of that type in which the work is fed intermittently by the cooperating action of a work support and presser foot constructed and arranged to engage respectively the welt and outsole of a shoe. Referring particularly to Figures 8 to 14, the work support is indicated at 2 and the presser foot at 4, both of these parts being mounted upon a feed carriage in the form of a slide 6 mounted for advancing and retracting movements in the line of feed on fixed guides 8 and 10. The work support 2 is rigidly secured to an arm projecting forwardly from the slide 6 and the presser foot is secured to the forwardly extending arm of a presser foot lever 12 pivotally mounted upon the slide 6. The lever 12 is connected to the cam shaft of the machine through mechanism hereinafter described, by which the lever is actuated to cause the work to be gripped between the presser foot 4 and the work support 2 and to be released during each stitch forming cycle of the machine. The feed slide 6 is advanced and retracted in the line of feed during each stitch forming cycle by the mechanism to be described and these movements are timed with relation to the movements of the presser foot lever 12, so that the advancing movement to feed the work takes place while the work is clamped,

and the retracting movement takes place while the work is released. The work is thus fed past the stitch forming devices of which the curved awl and the curved hook needle are indicated respectively at 14 and 16.

For imparting the advancing and retracting movement in the line of feed to the feed carriage 6, a toggle is provided comprising the members 18 and 20. These members are connected by the central pivotal joint 22. The member 18 is pivotally connected at 24 to the feed slide 6, and the member 20 is pivotally connected at 26 to a support 28. The pivotal centers 24, 22 and 26 are so arranged that when these centers are in line, the feed slide 6 is at the extreme limit of its advancing feeding movement. The feed slide is actuated by reciprocating the central joint 22 of the toggle and to this end the member 18 of the toggle is connected by means of a link 30 to the upper end of a pivotally mounted support 32 which is actuated from the cam shaft of the machine through connections including a link 34 also connected to the upper end of the arm 32.

To vary the action of the toggle so as to vary the feeding movements imparted to the slide 6, the support 28 which carries the pivotal center 26 of the toggle is pivotally mounted in alignment with the central joint 22 of the toggle when the toggle is in straightened condition, and means are provided for adjusting the support 28 about its pivot so as to change the position of the pivotal center 26. As will be apparent from an inspection of Figure 11, an adjustment of the support 28 in a counter-clockwise direction will act to increase the length of feeding movements, while an adjustment of the support 28 in a clockwise direction from the position indicated in Figure 11 will act to decrease the length of feeding movements. As viewed in Figure 11, the member 18 of the toggle is at the limit of its swinging movement in a counter-clockwise direction, and the central joint 22 of the toggle is in line with the centers 24 and 26. At the end of each feeding movement, the central joint 22 of the toggle always returns to the same point, and this point is substantially in line with the centers 24 and 26, regardless of the adjustment of the support 28, the displacement of the point 22 from this line, under any adjustment of the support 28, being so slight as to have no appreciable effect on the position of the feed slide at the end of its advancing movement.

As a convenient means for adjusting the support 28 and holding it securely in adjusted position, the support is provided with a gear segment 36 which meshes with the gear segment 38 upon the inner end of the adjusting lever 40 pivotally mounted upon a stud 42 secured to a fixed portion 44 of the machine frame. At its outer end the lever 40 extends over a segmental plate 46 provided with perforations 48 in which pins may be inserted to limit the swinging movement of the lever 40 in adjusting the support 28.

To hold the adjusting lever 40 in any position to which it may be moved, a clutch mechanism is provided comprising two one-way clutch rolls 50 seated in recesses in a block 52 secured to the outer end of the adjusting lever 40 and interposed between a segmental surface 54 on the outer edge of the plate 46 and inclined surfaces 56 on the block 52. A coiled spring 58 extending through a block 60 at the lower end of a stud secured in the lever 40 and interposed between the balls 50 normally acts to force the balls away

from each other into clutching position so that the adjusting lever 40 is held from movement in one direction by one ball and from movement in the other direction by the other ball.

5 The clutching mechanism is controlled and the adjusting lever 40 is actuated by a control lever 62 which is mounted upon the stud 42 and extends outwardly over the lever 40 and over the clutch mechanism. At its outer end the control lever 62 is provided with arms 64 which extend downwardly outside of the balls 50 and are provided at their lower ends with set screws 66 arranged, when the lever 62 is swung in either direction, to engage one or the other of the balls 50 and move it into inoperative position against the tension of the spring 58. The control lever 62 thus has a limited movement independently of the adjusting lever 40 and acts during this limited movement to actuate the clutch mechanism to release the adjusting lever 40. Continued movement of the control lever 62 in the same direction thereafter acts to move the adjusting lever. A spring pressed plunger 68 mounted in the adjusting lever 40 is arranged to 25 engage a recess in the lower surface of the control lever 62 and hold the control lever normally out of engagement with the clutch rolls.

The curved awl 14 and the curved hook needle 16 are clamped respectively in the awl segment 70 and the needle segment 72, which segments are mounted to oscillate concentrically upon a fixed stud 74 (see particularly Figs. 18 to 21). The needle and awl segments are so supported that the needle and awl are in the same vertical plane and operate in this plane without any movement back and forth in the direction of feed. The needle guide indicated at 76 is secured to a hub 78 and this hub is also supported from the stud 74.

40 As affording a simple and compact construction and one which permits a relative adjustment of the needle and awl segments to bring the needle and awl into the same plane upon a change in the size of either the needle or the awl, or when 45 for any reason these parts become displaced with relation to each other, the needle and awl segments and the hub of the needle guide are arranged on the stud 74 as follows. The hub of the needle guide and the awl segment are mounted in line with each other directly on the stud and the needle segment is mounted on the hub of the needle guide between a flange on the hub of the needle guide and a plate 80 mounted on the stud 74 between a shoulder on the stud and the adjacent end of the hub of the needle guide, the plate being held from rotation by a pin 82 projecting from the plate into the arm 84 of the fixed bracket in which the stud is secured. Between the hub of the needle guide and the awl segment 70 a plate 86 is interposed and is pressed yieldingly against the adjacent end face of the hub of the needle guide by coiled springs 88 seated in recesses in the awl segment. The awl segment is mounted on the stud 74 between the plate 86 and a fixed bracket arm 90. The springs 88 thus tend to force the hub of the needle guide with the needle segment mounted thereon and the awl segment in opposite directions and hold these parts securely in position with the awl segment bearing against the bracket arm 90 and with the hub of the needle guide and the needle segment bearing against the fixed plate 80. One end of the stud 74 is securely clamped in the bracket arm 84 by means of a binding bolt 92 and the other 75 end of the stud extends through a supporting

perforation in the bracket arm 90. At its end adjacent the bracket arm 90 the stud 74 is provided with an internal screw thread engaged by an adjusting screw 94, the flanged head of which engages the outer surface of the bracket arm 90. 5 This screw provides a means for moving the stud 74 longitudinally when released by the clamping bolt 92 to adjust the awl and needle segments relatively to each other longitudinally of the stud to thereby bring the needle and awl into the same 10 vertical plane.

The needle and awl segments are actuated, as hereinafter described, to cause the needle and awl to enter and withdraw from the work. To actuate the needle guide in the desired manner 15 so as to support the needle properly during its work piercing and loop drawing movements, the plate 86 which bears against the end surface of the hub of the needle guide is connected to the awl segment by means of pins 96 rigid with the 20 plate and projecting into recesses in the hub of the awl segment. The movements of the awl segment thus tend to move the needle guide through the frictional engagement of the plate 86 with the hub of the guide and the guide is 25 actuated in the desired manner.

In addition to the needle, the thread handling devices acting on the needle thread consist of a needle threading looper, a thread arm for drawing out a bight of thread between the looper and 30 the work, a loop taker in the form of a shuttle for passing a loop of needle thread over the locking thread case, a loop spreader to spread the loop for the loop taker, a take-up, a thread lock and a needle thread pull-off or thread 35 measurer.

The looper comprises a thread eye 98 formed (see Figs. 6, 15, 16, 22 and 23) in the outwardly bent arm of a rod secured so as to be capable of longitudinal adjustment in an axial socket at the 40 upper end of a downwardly and rearwardly extending shaft 100. The shaft 100 is mounted in a fixed bracket 102 and is provided at its lower end with a gear segment 104, meshing with a gear segment 106 at the forward end of an 45 actuating lever 108. This lever is pivotally mounted on the machine frame and is oscillated from the cam shaft of the machine through connections hereinafter described. While the needle is through the work, the looper, in co-operation with the thread arm, is oscillated to 50 carry the thread outside of and across the circle of the needle to thread the needle, as clearly shown in Figures 29 and 30.

The thread finger, indicated at 110, is secured 55 to the upper end of a lever 112 pivoted at its lower end upon the fixed bracket 102 and arranged to swing in a vertical plane across the upper end of the looper when the looper is in the position indicated in Figures 22 and 23. As 60 the needle makes its work piercing stroke the thread finger is moved rearwardly across the top of the looper and draws out a bight of thread between the looper and the work, as indicated in Figures 29 and 30. The mechanism for actuating 65 the thread finger will be hereinafter described.

The loop spreader (see Figs. 6, 15 and 26 to 34) comprises an arm 114 secured to a block 116 integral with a laterally extending stud 118 journaled in fixed bracket arms 120 and 122 70 (see particularly Fig. 6). The lower end of the loop spreading arm projects slightly across the plane of the needle and when actuated moves from its rearward position forwardly across the path of the needle to engage one side of the 75

needle loop and extend it to the position indicated in Fig. 31. The loop spreader is actuated from the cam shaft of the machine through connections hereinafter described which comprise a lever arm 124 clamped to the supporting stud of the spreader carrying block 116 between the fixed brackets 120, 122.

The loop taker, which takes the spread loop from the needle and loop spreader and passes it over the thread case for the locking thread, is indicated at 126 (see Figs. 3, 17 and 25 to 34). This loop taker is in the form of a discoidal rotary shuttle which passes completely through the needle loop. It comprises a hollow cylindrical body closed at its rear end and open at its forward end to receive the cylindrical locking thread case 128. This locking thread case is loosely mounted upon a supporting stud 130 extending forwardly from the rear wall of the shuttle and forming a bearing for the sleeve 132 projecting rearwardly from the rear wall of the thread case. The sleeve 132 forms a bearing for a bobbin 134 on which the locking thread is wound. The locking thread leads from the bobbin through a passageway 136 in the cylindrical wall of the thread case and then passes diametrically across the outer front face of the thread case along passageways formed in a projection 138 at the top of the thread case and a projection or nose 140 at the bottom of the thread case. The shuttle body at its inner and outer ends is provided with beveled surfaces to facilitate the passage of the needle loop over the shuttle, and between these surfaces is provided with a bearing groove engaged by a circular raceway 142 by which the shuttle is supported in the machine. As shown in Figs. 16 and 17, the raceway 142 is provided with channels 144 through which lubricating oil is supplied to the bearing surfaces of the shuttle. The periphery of the shuttle is interrupted by a recess shaped to receive a shuttle driving arm 146 and to form the loop taking beak 148 and heel 150.

During the operation of the machine, the shuttle is rotated continuously in the same direction and the locking thread case is held from rotation by a retaining arm 152, the lower end of which is provided with a notch engaging the nose 140 at the bottom edge of the case. To provide ready access to the thread case, the retaining arm 152 is pivotally mounted on the frame of the machine near its upper end by means of a pivot shaft 154 so that the lower end of the retaining arm may be swung outwardly away from the thread case, as indicated in dotted lines in Figure 2. The retaining arm is normally held in retaining position in front of the thread case by means of a pivotally mounted latch 156 arranged to engage a projecting pin 158 at the upper end of the retaining arm above the pivot shaft 154. A spring 160 stretched between the latch 156 and the upper end of the arm 152 serves to retain the latch in engagement with the pin 158 until the latch is raised by the operator when the spring acts to swing the retaining arm away from the thread case.

After the needle loop is carried over the top of the shuttle, it is pulled down from the shuttle and into the work by the take-up mechanism illustrated particularly in Figures 8, 35, 36 and 37. This take-up mechanism comprises two arms 162 and 164 pivotally mounted one above the other to swing in substantially the same vertical plane. At their outer ends these arms carry respectively take-up rolls 166

and 168 over which the needle thread passes in its travel from the source of supply to the looper. In taking up the thread, the take-up rolls 166 and 168 cooperate with fixed guide rolls 170 and 172, these guide rolls being arranged so that the thread coming from the supply passes first around the roll 170, then over the upper take-up roll 166, then over the lower take-up roll 168, then upwardly to the guide roll 172 and from this roll to the looper. The take-up arms 162 and 164 are arranged to move from the position indicated in Figure 36, in which they are substantially horizontal and parallel, to the position indicated in Figure 35, in which they are substantially vertical and in line with each other. In so moving, the arms 162, 164 cause the take-up rolls 166 and 168 to take up the thread simultaneously in two loops and, by reason of the fact that the arms are substantially in alignment at the limit of their taking-up stroke, the amount of thread taken up is always the same, and is not affected by any overthrow of the arms. The take-up arms are actuated from the cam shaft of the machine through mechanism hereinafter described, which mechanism comprises intermeshing gear segments 174 on the hubs of the arms, a gear segment 176 on the hub of the lower arm 164, and a gear segment 178 meshing with the gear segment 176 and carried at the outer end of one arm of a lever 180.

In the operation of the machine illustrated in the drawings, the depth to which the loop of needle thread is drawn into the work by the take-up is determined primarily by a thread measuring and gripping mechanism acting on the locking thread. This locking thread measuring or pull-off mechanism is best illustrated in Figures 6, 10, 15, 16, 17, and 25 to 34, and comprises two gripping jaws 182 and 184 arranged to act on the locking thread between the projections 138 and 140 on the face of the thread case. These jaws have a reciprocating movement back and forth along the lead of the thread and the jaw 184 has a movement towards and from the jaw 182 to cause the jaws to grasp and release the thread. To give the jaws these movements, the jaw 182 is mounted rigidly on the lower end of a slide 186 and the jaw 184 is pivotally mounted upon the slide. The jaws 182 and 184 are located directly in front of the thread case and, in order to provide for the removal of the jaws from in front of the thread case so as to permit access to the thread case, the slide 186 upon which the grippers are carried is mounted in the bobbin case retaining arm 152. The slide, together with the gripping jaws, are thus moved away from the thread case with the arm.

To actuate the slide 186 a train of mechanism is provided connecting the slide with the work feed carriage 6. These connections (see particularly Figures 6, 10 and 17) comprise an arm 188 pivotally mounted upon a projection from the thread case retaining arm 152 and provided with a gear segment meshing with a rack at the upper end of the slide 186. An arm 190 is secured to the pivot stud of the arm 188 and is connected by means of a link 192 to the upper end of a lever arm 194. The pivot stud of the arm 194 is journalled in a fixed portion of the machine frame and to this pivot stud is securely clamped a downwardly extending lever arm 196 to the lower end of which is adjustably secured a pivotally mounted block 198 engaging a slot 200 in the feed carriage 6. It will be noted that the link 192 is provided at each end with a uni-

versal joint and that the link is in axial alignment with the pivot stud 154 of the thread case retaining arm 152 so that the swinging movement of the retaining arm into and out of operative position is not interfered with.

The movable jaw 184 of the locking thread measuring gripper is in the form of a leaf spring and is secured to the lower end of a lever 202 pivotally mounted on the slide 186. In order 10 to move the jaw 184 towards and from the jaw 182 the lever 202 is extended upwardly beyond its pivot and is provided with a roll engaging a vertical slot in a cross slide 204 mounted in the thread case retaining arm 152. As providing a 15 simple and efficient means for reciprocating the slide 204 to open and close the gripper jaws, the slide is provided at one end with a roll 206 which engages a cam groove formed in a block secured to the carrier block 116 of the loop spreader 114. 20 The operation of the locking thread gripping and measuring mechanism will be clearly understood from an inspection of Figures 25 to 34 which illustrate the position of the gripper jaws with relation to the positions of the shuttle and other 25 thread handling devices during the formation of the stitch. Starting with the parts in the position illustrated in Fig. 25, it will be noted that the grippers 182, 184 are in gripping engagement with the thread at the upper limit of their reciprocating movement, and that the locking thread has been pulled into the work by the action 30 of the take-up, and that the locking thread is taut from the lock to the grippers. At this point in the operation, the gripping jaws grasp the thread with sufficient firmness to accurately 35 determine the location of the thread lock in the work. After the stitch is set, the locking thread gripper moves downwardly to the position illustrated in Figs. 27 and 28, thereby pulling thread 40 from the bobbin and supplying slack thread between the gripper and the work. The grippers remain in this position during continued operation of the thread handling devices, as indicated in Figs. 29 and 30. As the loop of needle 45 thread is spread, as indicated in Figures 31 and 32, the jaws of the thread gripper release the thread and, while the needle loop is being pulled from the shuttle, the gripping jaws in open condition retract to the position indicated in Figures 33 and 34. At this point in the operation, 50 it will be noted that the slack in the locking thread has been taken up by the action of the needle loop on the locking thread, and that the threads are in condition to be pulled into the work. At this point in the operation, the jaws 55 of the thread gripper close on the thread, as indicated in Figure 26, and remain in gripping engagement with the thread while the thread loop is being pulled into the work and the stitch is being set.

The locking thread measuring and gripping mechanism above described is well adapted to cooperate alone with the take-up in determining the location of the thread lock in the work. The illustrated machine, however, is also provided with a needle thread pull-off or thread measuring mechanism, and with a thread lock to insure the proper handling of the needle thread and to cooperate with the locking thread measuring and gripping mechanism in securing a uniform appearance of the stitches and the desired location of the thread locks without danger of breaking the thread or injuring the work. This needle thread pull-off and locking mechanism is best shown in Figs. 8, 35, 36, and 37. The needle

thread pull-off and measuring mechanism comprises a pull-off arm 208 pivotally mounted on the fixed portion of the machine frame and provided, at its lower end, with a thread eye through which the needle thread passes on its way from the supply to the guide roll 170. This pull-off arm cooperates with a thread measuring arm 210 pivotally mounted on a fixed portion of the machine frame and provided at its lower end with an open ended loop through which the eye of the 10 pull-off lever 208 is arranged to pass. The thread measuring arm 210 is connected to the presser-foot mechanism hereinafter described through a connecting link 212, a bell crank 214, and a connecting rod 216 so that the position of the loop 15 portion which cooperates with the eye of the pull-off is determined by the thickness of the work. The pull-off arm 208 is actuated from the cam shaft through connections hereinafter described to carry the thread eye through the slot 20 of the thread measuring arm so as to pull off an amount of thread determined by the position of the thread measuring arm 210, as clearly shown in Fig. 35. This movement of the needle thread pull-off takes place simultaneously with the movement of the take-up in drawing the last needle 25 loop from the shuttle down into the work. At this time in the operation, the needle thread is locked against movement by a thread locking arm 218 pivotally mounted in the machine frame 30 and provided at its lower end with a surface arranged to press the needle thread against the surface of the guide roll 170 and lock the roll with the thread against movement. During the passage of the needle loop around the shuttle, the 35 take-up arms 162 and 164 and the pull-off arm 208 return to the position illustrated in Figure 36 to give up to the shuttle the amount of thread required to enable the loop of needle thread to pass over the shuttle without pulling any more 40 thread from the supply. The thread locking arm 218 is actuated from the cam shaft of the machine, as hereinafter described.

The presser-foot actuating mechanism of the illustrated machine is constructed and arranged 45 to hold the presser-foot yieldingly in contact with the work during the backfeed of the feed carriage with the work support and presser-foot, then to force the presser-foot firmly against the work to grip the work between the presser-foot and work support, and to lock the presser-foot firmly 50 in gripping engagement with the work during the work feeding movement of the feed carriage and also during the movement of the needle in retracting from the work. This presser-foot actuating mechanism (see particularly Figures 38 to 41) comprises a Horton clutch, the driving member of which is actuated from the cam shaft of the machine, and the driven member of which is connected to the presser-foot. The driven member 55 of the Horton clutch is indicated at 220 and comprises a ring surrounding a three-arm driving member 222. The driven member 220 is connected to the presser-foot by means of a rod 224 extending from a lug on the member 220 to the 60 upwardly projecting arm of the presser-foot lever 12. To allow for the feeding movement of the feed carriage upon which the presser-foot lever is mounted, the link is provided at each end with a universal joint, and at the forward end of the 65 link the universal joint is adjustably secured in a slot in the presser-foot lever. A coiled spring 226 connected to the lug on the member 220 tends to move the member in a direction to force the presser-foot against the work with a yielding 70 75

pressure. The driving member 222 of the clutch is secured to an oscillating shaft 228 and is provided between its arms with recesses in which are located the gripping rolls 230 of the clutch. 5 The bottoms of the recesses are formed as cam surfaces which, as the driving member is rotated in a clockwise direction, as viewed in Figure 40, causes the rolls to be wedged between the driven and driving members so that the members are locked together and the driven member 220 is positively actuated. This movement of the driven member 220 forces the presser-foot firmly against the work so that the work is clamped between the presser-foot and the work support. 10 Upon the return movement of the driving clutch member 222 in a counter-clockwise direction, the rolls 230 are freed from gripping engagement with the two members of the clutch by the action of the spring plungers 232 seated in the arms 15 of the driving member and bearing against the rolls. The initial position of the rolls and, consequently, the extent of the clockwise movement imparted to the drive member 220 is determined by a series of stop projections 234 which extend 20 from plates 236 adjustably mounted in a bracket 238 supported on the reduced end of the shaft 228 and rigidly secured to the machine frame. To limit the movement of the presser-foot towards the work support under the force of the 25 spring 226, and thus avoid possible breakage, of the parts in case the presser-foot mechanism is actuated with no work in the machine, a spring pressed stop plunger 240 is arranged in the path 30 of a lug 242 projecting from the driven member 220 of the clutch. This spring plunger, while limiting the movement of the presser-foot towards the work support permits a slight movement of the presser-foot actuating and locking mechanism in case the mechanism is operated 35 with no work in the machine. The connecting rod 216, above referred to as a part of the connections between the presser-foot actuating mechanism and the thread measuring arm 210, is connected at its upper end to a lug projecting 40 from the driven member 220 of the clutch. 45 The shaft 228 to which the driving member 222 of the Horton clutch is secured is oscillated by connections from the cam shaft 244 of the machine through connections which comprise a cam actuated lever 246 (see Fig. 38) which is 50 pivotally mounted on a long supporting shaft 248 extending forwardly of the cam shaft. The lever 246 is provided with two upwardly extending arms, one of which is provided with a cam follower engaging a groove in a cam disk 250 secured to the cam shaft and the other of which is connected by a link 252 to an arm 254 pivotally mounted upon a shaft 256. The arm 254 forms 55 one member of a toggle joint, the upper member 258 of which extends from the pivotal connection of the link 252 and arm 254 to the outer end of an arm 260 secured to the end of the shaft 228 remote from the driving member 222 of the Horton clutch (see Fig. 39). The toggle joint 60 formed by the members 254 and 258 is arranged so that the joint is in straightened condition at the limit of the actuating movement of the driving clutch member so that the toggle joint through the driving and driven members of the Horton clutch positively locks the presser-foot in work 65 clamping position.

The machine illustrated in the drawings is provided with a gage to bear against the edge of the shoe sole and determine the position of the out- 70 seam on the sole and with a channelling cutter

or fudge knife to cut a channel in the welt to receive the stitches. The construction and operation of these parts will be understood from an inspection of Figures 4, 6, 7, 8, 15, and 24.

The edge gage indicated at 262 is formed at 5 the forward end of a slide mounted in a guideway in the fixed bracket 90 of the machine frame so as to be capable of a movement transversely of the line of feed. At its rear end the edge gage slide is provided with a slotted projection which 10 is engaged by a roll at the upper end of a vertically arranged lever 264. The lever 264 is pivotally mounted intermediate its ends, at 266 on a fixed portion of the machine frame, and at its lower end is provided with a roll which 15 engages a cam groove in an arm 268 rigidly secured to a rock shaft 270 (Fig. 8.) The shaft 270 is journalled in bearings in the bracket 44 and extends outwardly beneath the adjusting lever 62 of the work feeding mechanism. At its outer end, 20 the shaft 270 is provided with a downwardly extending handle 272 by means of which the shaft 270 can be rocked by the operator to move the edge gage as may be desired (Fig. 4.) Also secured to the outer end of the shaft 270 is an 25 upwardly projecting arm 274, the upper end of which is formed as a segment extending beneath and across the feed adjusting lever 62 and provided with a series of perforations in which pins may be placed to contact with either side of the 30 feed adjusting lever. By means of this construction, the edge gage adjusting mechanism and the feed adjusting mechanism may be connected, if desired, so that both adjustments can be made by a single movement of either the hand lever 35 272 or the adjusting lever 62. To limit the in and out movement of the edge gage, a collar 276 is secured to the shaft 270 and is provided with adjustable stop screws 278 and 280 arranged to contact with adjacent portions of the bracket 44 40 as the shaft is rocked in opposite directions (Fig. 3.)

The welt channelling cutter or fudge knife is indicated at 282 and is formed at the upper offset end of a rod removably and adjustably secured 45 in a socket, at the upper end of a slide 284 mounted in a vertical guideway in the frame bracket 102. The knife 282 is arranged to extend forwardly through the needle and awl slot in the work support and when in operative position remains stationary during the forward and 50 retracting movements of the feed carriage, thereby cutting a channel in the welt as the shoe is fed past the knife by the feeding movement of the work support and presser-foot. To enable the 55 channelling cutter to be moved into and out of operative position, as is common in outsole stitching machines, the slide 284 is provided with a projecting pin 286 which is engaged by a slot in one arm of a bell crank 288 pivotally mounted 60 on the frame bracket 102. The other arm of the bell crank 288 is slotted and is engaged by a pin 290 projecting from the edge gage actuating lever 264. This construction causes the welt channelling cutter to be projected into operative position 65 above the work support when the edge gage is moved forwardly by the lever 264 and causes the cutter to be withdrawn into inoperative position below the surface of the work support when the edge gage is returned to its rearward position. 70

An outsole stitching machine necessarily comprises a large number of parts, many of which have an intermittent or irregular movement. These parts, in order to be strong and durable, must be large and heavy. The momentum of 75

these parts, when operated at high speed, is considerable, and renders stopping of the machine without injurious shock or jar extremely difficult. In the illustrated machine which is designed for 5 operation at high speed, the stopping of the operating parts in the desired position to permit removal of the shoe is accomplished by actuating the principal thread manipulating and work feeding devices from the cam shaft through separate trains of mechanism, and by providing in 10 these trains of mechanism, elements adapted to be disconnected, whereby the principal operating devices of the machine can be brought to rest at a predetermined time in the cycle of operations 15 without simultaneously stopping the rotation of the cam shaft and some of the light and uniformly moving parts actuated thereby. In the illustrated machine movable disconnectible elements are provided in the trains of mechanism 20 for actuating the needle and awl, feed mechanism, take-up, needle threading looper, loop spreader and needle thread lock. Also, the locking thread gripping and measuring mechanism is actuated through connections from the work 25 feed mechanism, the needle guide is actuated through connections from the needle actuating mechanism, and the needle thread pull-off is actuated through connections from the take-up actuating mechanism so that these parts are also 30 brought to rest with the other thread handling and work feeding devices. The trains of mechanism between the cam shaft and the spreader, looper, feed carriage, awl, needle and take-up are 35 similar in that each train comprises a lever in engagement with a cam on the shaft and a link movable into and out of engagement with the lever. The cam actuated lever for the spreader is illustrated in side elevation in Fig. 38, and is indicated at 292. This lever and the corresponding 40 levers of the mechanisms for actuating the looper, feed carriage, awl, needle and take-up are pivotally mounted on the supporting shaft 246. The lever 292 is provided with a cam follower 45 engaging a groove in the disk 294. The position of this cam disk with relation to the other cam disks of the cam shaft 244, is indicated in Figures 5 and 7. The detachable link in the mechanism for actuating the spreader is indicated at 296. This link is arranged in substantially horizontal position and at its forward end is pivotally connected to the lower end of a two arm lever 298, the upper end of which is connected by a 50 link 300 to the arm 124, hereinbefore described as secured to the pivot stud of the carrier for the loop spreader. Near its rear end and on its under side, the link 296 is provided with a notch 302 adapted to engage a pin 304 projecting from the cam actuated lever 292. While the machine is in 55 operation, the notch 302 is in engagement with the pin 304 so that the two parts are positively connected and the spreader is actuated from the cam shaft. The link is held in this position by means of a coil spring 306 stretched between a 60 point on the link and a fixed point on the machine frame. The cam levers and disconnectible links of the trains of mechanism for actuating the looper, feed carriage, awl and needle are shown in plan in Fig. 7. Referring to this figure, and to Figure 5, the cam actuated lever of the looper actuated mechanism is indicated at 308 and the disconnectible link at 310. The cam lever 308 is provided with a follower engaging a groove in 65 the cam disk 294. The cam actuated lever of

the mechanism for actuating the feed carriage is indicated at 312 and the disconnectible link at 34. The cam lever 312 is provided with a cam follower engaging a groove in the cam disk 314. The cam levers for actuating the awl and needle are indicated respectively at 316 and 318. The cam lever 316 is provided with a follower engaging a groove in the cam disk and the cam lever 318 is provided with a cam follower engaging a groove in the cam disk 320. The disconnectible links of the awl and needle actuating mechanisms are indicated at 322 and 324. The cam lever and disconnectible link of the mechanism for actuating the take-up appear in plan in Figure 7 and in side elevation in Figure 35. 10 The cam actuated lever is indicated at 326 and the disconnectible link at 328. The cam lever 326 is provided with a cam follower engaging a groove in the cam disk 320. 15 The connections between the detachable links 20 and the spreader and feed carriage have already been described. To actuate the looper, the forward end of the disconnectible link 310 is pivotally connected to a lever arm 330 pivotally mounted on a supporting pivot shaft 332 (see Fig. 38) and the upper end of this arm is connected by a link 334 to the looper actuating lever, 108, hereinbefore described. To actuate the awl, the link 322 (see Fig. 16) is pivotally connected at its forward end to the downwardly extending arm 30 of a bell crank 336 pivotally mounted in a fixed portion of the machine frame on the supporting shaft 338 and provided at the forward end of its horizontal arm with a gear segment meshing with teeth formed on the awl carrying segment 38. To actuate the needle the forward end of the link 324 is pivotally connected to the downwardly extending arm of the bell crank 340 pivotally mounted on the shaft 338 beside the bell crank 336 and provided at the forward end of its horizontal arm with a gear segment meshing with teeth on the needle carrying segment 72. 35 To raise the disconnectible links out of engagement with the cam actuated levers upon stopping the machine, a controller comprising the shaft 256 and a series of arms 344 secured thereto is utilized. An arm 344 is associated with each disconnectible link and each arm is provided at its forward end with a block or plate 346 having on its upper side a recess arranged to engage a pin 348 projecting laterally from the rear end of the corresponding disconnectible link. While the machine is in operation, the arms 344 are in lowered position, as indicated in dot and dash lines in Fig. 42, with the blocks 346 extending beneath the pins 348 and out of engagement therewith. While the machine is in operation, as has been stated, the disconnectible links are in their lowered position with their notches in actuating engagement with the pins on the cam actuated levers. At a certain point in the revolution of the cam shaft, the shaft 256 is rocked in a clockwise direction, as viewed in Fig. 35, as will be hereinafter explained, and the disconnectible links are raised out of engagement with the cam actuated levers. At this point in the revolution of the cam shaft the cam actuated levers are stationary, due to the configuration of the cam grooves, and the pins 348 on the disconnectible levers are in position to be engaged 60 by the recesses in the blocks 346. After the disconnectible links are raised from the cam actuated levers, the links are held from movement by the engagement of the pins 348 with the recessed blocks 346 and the actuated parts are 65 70 75

brought to rest while the cam shaft 244 is permitted to continue its rotation.

Upon starting the machine, the control shaft 256 is rocked in the opposite direction at the point in the revolution of the cam shaft when the projecting pins on the cam actuated levers are in alignment with the recesses in the disconnectible links. This rocking movement of the control shaft returns the arms 344 to their lowest position and permits the links to actively engage the cam levers. The links are pulled down by their springs corresponding to the spring 306. To insure the downward movement of the links each arm 344 is provided at its forward end with a plate 350 overlying the corresponding pin 348 on the disconnectible lever.

The mechanism for rocking the control shaft 256 upon stopping and starting the machine comprises stopping and starting cams formed peripherally on a cam disk 352 (see Figs. 42, 43 and 44). This cam disk is mounted to rotate with the cam shaft, but is movable longitudinally of the shaft to bring either the starting or stopping cam into operative position with relation to a starting and stopping lever. The cam disc is moved longitudinally of the cam shaft through connections from the starting and stopping treadle of the machine, as will be hereinafter described. The starting and stopping lever is provided with two arms, one of which is indicated at 354 and may be termed the starting arm and the other of which is indicated at 356 and may be termed the stopping arm. The starting and stopping arms are provided with cam followers 358 and 360 and these cam followers are so located that a longitudinal movement of the starting and stopping cam disk will move one of the cams out of the plane of its follower before the other cam is brought into the plane of its follower. The stopping cam is indicated at 362 and the starting cam at 364.

When the machine is running, the starting and stopping lever is in the position indicated in Figure 42 in which position the stopping cam 362 is out of the plane of the cam follower 360. Upon stopping the machine, the starting and stopping cam disk is moved to bring the stopping cam 362 into the plane of the follower 360 and, as the cam shaft approaches the position indicated in Figure 43, the starting and stopping cam lever is moved to stopped position where it remains until the machine is again started. Upon starting the machine the cam shaft is first connected to its driving means as will be hereinafter described and thereafter the starting and stopping cam disk is moved to bring the starting cam 364 into the plane of the cam follower 358. As the cam shaft approaches a predetermined angular position, the starting and stopping lever is actuated in a clockwise direction, as viewed in Figures 42 and 43, and thereafter, by reason of the connections to the control rock shaft 256, the starting and stopping lever is returned to running position indicated in Figure 43.

The connection between the starting and stopping cam lever and the rock shaft 256 comprises a bell crank 366 mounted upon the frame of the machine, a link 368 connecting the upper end of the arm 356 of the stopping and starting cam lever with one arm of the bell crank and a link 370 connecting the other arm of the bell crank with an arm 372 secured to the shaft 256. The arrangement of these parts is such that when the starting and stopping lever is actuated by the stopping cam, the shaft 256 is rocked in a clockwise direction, as viewed in Figures 42 and 43, to raise the disconnectible links from their actuating cam levers, and as the parts reach the limit of their movement, the toggle joint formed by the horizontal arm of the bell crank 366 and the link 370 becomes straightened and locks the parts in the position indicated in Figure 43. Upon the reverse movement of the starting and stopping cam lever under the influence of the starting cam 364, the shaft 256 is rotated in a counter-clockwise direction, and as soon as the toggle formed by the bell crank 366 and the link 370 is broken, the weight of the arms connected to the shaft 256 continues the rocking movement of the shaft until the parts assume the position indicated in Figure 42. The movements of the parts in both directions are limited by adjustable stop screws 374 arranged to engage the bell crank 366 above and below its pivot.

Upon stopping the machine the presser-foot is lifted from the work and retained in this position until the machine is again started. To accomplish this result, an arm 376 is mounted upon the rock shaft 256 and extends at its forward end beneath a lug 378 on the rod 216 which is connected to the driven member 220 of the presser-foot actuating clutch. To avoid breakage or injury to the parts in case the lug 378 is engaged by the arm 376 while the member 220 is held against movement, the arm 376 is connected to the shaft 256 so as to be capable of a slight yielding movement. To this end the arm 376 is loosely mounted on the shaft 256 and is yieldingly connected to an arm 380 rigidly secured to the shaft, the yielding connection comprising a coiled spring 382 seated in the arm and tending to force a projection 384 on the arm 376 towards a projection on the arm 380. The extent to which the presser foot can be lifted on stopping the machine is limited by an adjustable stop rod 385 (see Fig. 17) arranged to engage the presser foot lever 12.

As has been stated, the starting and stopping cam disk which actuates the mechanism for disconnecting many of the actuated parts of the machine from the cam shaft is moved longitudinally of the cam shaft through connections from the starting and stopping treadle by which the cam shaft is disconnected from its driving means. These connections comprise a cam shifting arm 386 forked at its lower end to engage a groove in the cam disk 352 and secured at its upper end to a rock shaft 388 mounted in the frame of the machine at right angles to the cam shaft. To the outer end of the shaft 388 is secured a horizontally arranged cross bar 390, one end of which is forked and provided with oppositely disposed stop screws 392 cooperating with a fixed lug 394 on the frame of the machine to limit the movement of the cross bar, and the other end of which is provided with a pivotally mounted block 396 through which the upper end of the treadle rod 398 extends. This block 396 rests upon a collar 400 secured to the treadle rod and is pressed down against the collar by means of a spring 402 coiled around the upper end of the treadle rod and interposed between the block 396 and a collar 404 secured to the rod. Downward movement of the treadle rod thus swings the cross bar 390 to rock the shaft 388 and move the starting and stopping cam disk 352 to starting position and, after the movement of the cross bar is stopped, continued downward movement of the treadle rod is permitted. Upon the return upward movement of the treadle rod, the cross bar 390 is held in the position to which

it has been moved by the downward movement of the rod until the collar 400 again contacts with the block 396 when the continued upward movement of the treadle rod actuates the cross bar in the opposite direction to return the starting and stopping cam to stopping position.

The downward movement of the treadle rod after the starting and stopping cam has been moved to starting position is utilized to connect the cam shaft to its driving mechanism and the upward movement of the treadle rod before the starting and stopping cam is shifted to stopping position is utilized to disconnect the cam shaft from its driving mechanism. The cam shaft is driven through intermeshing spiral gears from a cross shaft 406 on which is mounted a loose pulley 408 which is constantly rotated by a belt passing over the pulley and over a pulley 410 driven by a motor 412 in the base of the machine. The pulley 408 is provided with a clutch surface arranged to cooperate with a clutch member 414 mounted to rotate with the shaft 406 and to be moved longitudinally of the shaft into and out of engagement with the pulley 408. The movable clutch member 414 is actuated from the treadle rod 398 through connections which comprise a bell crank lever 416, the vertical arm of which is forked and engages a ring mounted on the clutch member 414 and the horizontal arm of which extends below a collar 418 on the treadle rod. During the downward movement of the treadle rod 398 the collar 418 engages the bell crank 416 and forces the clutch member 414 firmly into engagement with the driving pulley 408 after the starting and stopping cam 352 on the cam shaft has been moved to starting position. During the first portion of the upward movement of the treadle rod, the collar 418 is lifted from the bell crank 416 and the clutch member 414 is permitted to move out of clutching engagement with the driving pulley, this action taking place before the starting and stopping cam disk 352 is returned to stopping position.

The treadle rod is acted upon by a lifting spring 420 coiled around the rod and interposed between a collar on the rod and a lug on the base of the machine. At its lower end, the treadle rod is connected to the horizontal arm of a bell crank 422, the vertical arm of which is connected by a link 424 to the upwardly extending arm of a treadle lever 426. The upward movement of the treadle rod, when the treadle is released, is limited by an adjustable stop screw 428 arranged to engage the treadle lever 426.

The shuttle is rotated at a uniform speed through connections from the cross shaft 406 comprising a vertical shaft 428 which is driven from the shaft 406 through intermeshing spiral gears 430 and which drives the shaft 432, to which the shuttle driver 146 is secured, through intermeshing spiral gears 434. To provide a slip connection in the mechanism for driving the shuttle, one of the spiral gears 434 is loosely mounted on the shaft 432 and is clutched to the shaft by a toothed clutch member 436 splined on the shaft and held yieldingly in engagement with the spiral gear by a spring 438 coiled around the reduced rear end of the shaft 432 and interposed between the clutch member 436 and nuts on the end of the shaft. The gears through which the shuttle is driven are proportioned to impart two rotations to the shuttle during each rotation of the cam shaft. The driving mechanism for the shuttle is permanently connected to the cam shaft through the shaft 406 so that the shuttle

continues to rotate until the cam shaft finally comes to rest.

The mechanism for actuating the thread lock (see Figs. 35, 36 and 37) comprises a cam actuated lever 440 pivotally mounted on the supporting shaft 248 and provided with a cam follower bearing against the periphery of a cam 442 on the cam shaft. The cam follower is held in engagement with the cam by means of a coiled spring 444 stretched between the upper end of the lever and a fixed point on the frame of the machine. Upon the forward end of the horizontal arm of the cam lever 440 is pivotally mounted a bell crank 446, the vertical arm of which is provided with a cam follower engaging a cam groove in an arm projecting from the hub of the starting and stopping lever 354, 356 and the horizontal arm of which is provided with segmental gear teeth meshing with corresponding teeth on the horizontal arm of the thread locking lever 218. With this construction, the thread locking lever 218 is actuated at the proper time during the operation of the machine, but upon stopping the machine the locking lever is moved into inoperative position out of contact with the thread guide roll 170 by the action of the cam groove on the bell crank 446.

As has been described, many of the thread handling and work feeding devices of the machine are disconnected from the cam shaft upon stopping the machine. In addition to these devices, the pull-off for the needle thread and the thread finger are also disconnected from the cam shaft upon stopping the machine.

To secure this result the thread finger is actuated from the needle actuating bell crank 340 through a link 448 connecting the lever arm 112 on which the thread finger is mounted to the horizontal arm of the bell crank, as indicated in Fig. 16, and the pull-off for the needle thread is actuated from the lever 180 of the take-up mechanism through a link 450 connecting the upper arm of the lever 180 with the upper end of the pull-off lever 208 (see Figs. 35 and 36).

The supply of needle thread is held in a container 452, of well known construction (see Fig. 1). From this container the thread leads through the wax pot 454, also of well known construction, to the needle thread measuring and pull-off mechanism and then to the thread guide roll 170. In its passage from the guiding roll 170 to the take-up roll 166 (see Fig. 8), the thread passes through an eye in the end of an auxiliary take-up arm 456 projecting from a hub mounted on the supporting stud of the roll and acted upon by a spring 458 coiled around the hub and connected at its opposite ends to an arm and to the stud. This auxiliary take-up arm is useful in controlling slack in the thread given up by the take-up and more particularly while the needle loop is being spread by the loop spreader.

Certain features of the invention herein disclosed form the subject-matter of divisional applications as follows: Serial No. 79,281 relating to the driving and stopping mechanism patented November 9, 1937, No. 2,098,251; Serial No. 79,282, relating to the needle and awl supporting construction patented September 7, 1937, No. 2,091,997; Serial No. 79,283, relating to the presser-foot clamping mechanism patented November 9, 1937, No. 2,098,298; Serial No. 79,284, relating to the take-up mechanism patented November 2, 1937, No. 2,097,462; and Serial No. 79,285, relating to the mechanism for handling the needle and locking threads,—all filed May 12, 1936.

The nature and scope of the present invention having been indicated, and a machine embodying the several features of the invention having been specifically described, what is claimed is:—

- 5 1. A sewing machine having, in combination with the stitch forming devices, a feed carriage, a toggle, one member of which is connected to advance and retract the feed carriage and to cause the advancing movement to take place as the toggle is straightened, and a support on which the other member of the toggle is pivotally mounted, adjustable to vary the limit of the retracting movement of the feed carriage.
- 10 2. A sewing machine having, in combination with the stitch forming devices, a feed carriage, a toggle, one member of which is connected to advance and retract the feed carriage and to cause the advancing movement to take place as the toggle is straightened, a support on which the other member of the toggle is pivotally mounted, and means for adjusting said support about a center substantially in alignment with the central joint of the toggle when in straightened condition.
- 15 3. A sewing machine having, in combination with the stitch forming devices, a feed carriage, a toggle, one member of which is connected to advance and retract the feed carriage and to cause the advancing movement to take place as the toggle is straightened, a support pivotally mounted in alignment with the central joint of the toggle when in straightened condition, a pivotal connection between the other member of the toggle and said support, and means for adjusting said support.
- 20 4. A sewing machine having, in combination with the stitch forming devices, work feeding mechanism and means for adjusting said mech-

anism comprising an adjusting lever, and suitable connections to said mechanism, a locking plate, a clutch mechanism to lock the lever to the plate, and a control lever having a limited movement with relation to the adjusting lever acting during said movement to actuate the clutch to release the adjusting lever and, during a continued movement in the same direction, to actuate the adjusting lever.

5 5. A sewing machine having, in combination with the stitch forming devices, work feeding mechanism and means for adjusting said mechanism comprising an adjusting lever, and suitable connections to said mechanism, a locking plate, a clutch mechanism to lock the lever to the plate, a control lever having a limited movement with relation to the adjusting lever acting during said movement to actuate the clutch to release the adjusting lever and, during a continued movement in the same direction, to actuate the adjusting lever, and a positioning device normally holding the control lever out of engagement with the clutch.

10 6. A sewing machine having, in combination with the stitch forming devices, work feeding mechanism, means for adjusting said mechanism comprising an adjusting lever and suitable connections to said mechanism, a locking plate, a clutch mechanism comprising two one-way clutch devices for locking the lever against movement in opposite directions, and a control lever having a limited movement in opposite directions with relation to the adjusting lever acting, during said movement in either direction, to actuate one of said clutch devices to release the adjusting lever and, during a continued movement in the same direction, to actuate the adjusting lever.

BERNARD T. LEVEQUE.
